UNITED STATES PATENT OFFICE.

WILLIAM B. THOMAS, OF GREEN CAMP, OHIO.

ADJUSTABLE SWINGING GATE.

SPECIFICATION forming part of Letters Patent No. 374,856, dated December 13, 1887.

Application filed September 9, 1887. Serial No. 249,221. (No model.)

To all whom it may concern:

Be it known that I, WILLIAM B. THOMAS, a citizen of the United States, and a resident of Green Camp, in the county of Marion and State of Ohio, have invented certain new and useful Improvements in Adjustable Swinging Gates; and I do hereby declare that the following is a full, clear, and exact description of the invention, which will enable others skilled in the art to which it appertains to make and use the same, reference being had to the accompanying drawings, which form a part of this specification, and in which—

Figure 1 is a side view of my new and improved swinging and adjustable gate, showing the gate in its lowermost position. Fig. 2 is a side view of the same, showing the gate raised; and Fig. 3 is a detail view of the hinge-bar.

20 The same letters of reference indicate corresponding parts in all the figures.

My invention consists in a new and improved swinging and adjustable gate, which may be readily raised and lowered and secured in its 25 adjusted position to swing open and close at the height to which it is adjusted; and my invention will be hereinafter fully described and claimed.

Referring to the several parts by letter, A 30 and B indicate the fence posts between which my new and improved gate is hung, A indicating the post to which the gate is latched by means of any suitable form of latch, which forms no part of my present invention, and B 35 the post to which the gate is hinged, and which may be denominated the "hinge-post." This hinge-post B is higher than the latch-post A, and its side which is next to the gate is beveled longitudinally at each corner of the said side, 40 as shown at B², for the purpose hereinafter specified, while the same side of the post is beveled from a point about level with the upper end of the hinge-bar of the gate back and up to its upper end, as shown, so that the upper end of this post is less than one-half as thick through in that direction as its lower end.

C indicates the gate, which may be of any desired and suitable construction, the one that 50 I have here shown being of a plain rectangular form. To the rear stile of this gate is se-

cured the longitudinal hinge-bar D, which extends up longitudinally at the back of the said stile, this bar or rod being nearly as long as the stile and being provided at its lower end 55 and also at a point near its upper end with arms D', the said arms extending at right angles to the body of the bar and being adapted to pass through transverse apertures C C' in the gate-stile toward the upper and lower ends 60 of the same. These arms D' D' are screw-threaded, as shown, to adapt nuts E E to be screwed on each toward their inner ends before they are inserted through the apertures C' C' and to enable similar nuts, F F, to be 65 screwed on their outer ends on the inner side of the stile, by which means the hinge bar or rod is firmly secured to the gate.

The arms D' D' may be secured to the rod or bar D in any suitable manner; but I prefer 70 to construct the bar and its arms in one piece, as shown in the accompanying drawings, the bar being there shown with its lower end bent in at right angles to form the lower threaded arm, D', while the upper parallel arm is formed 75 or cast integral with it, and the upper end of the rod D rises above this upper arm and is formed with an eye or transverse perforation, D².

In the hinge-post B are secured the two eye-bolts G G, the threaded stems of which pass through transverse apertures in the said post, one above the other, as shown, and are held in position in the said post by means of nuts H H, screwed on their projecting rear ends. 80 The hinge-rod D of the gate passes through these eyes between the upper and lower parallel arms D' D', as shown, by which means the gate is hinged to the post B, and to the upper 85 perforated end of the hinge rod or bar D is secured the lower end of an adjusting-chain, I, of suitable length. Now in the beveled upper end of the hinge-post B, back of the central line of the post, is secured a hook, J, and by thus beveling the upper end of the hinge-post I am enabled to place the supporting-hook J immediately over the center of the 90 width of the hinge-post.

In operation the gate may be raised to any height until the lower arm, D', comes in contact with the lower eye, G, of the hinge-post, and is secured in its adjusted position by hook- 95

ing one of the links of the chain I over the hook J, when the gate will be held in its raised or adjusted position and can be swung easily to either side, opening both ways; and the 5 corners of the rear side of the rear gate-stile are beveled longitudinally, as shown at C, and as the longitudinal corners of that side of the hinge-post B next to the gate are also beveled, as before stated, it will be seen that the 10 gate can be swung open either way past right angles with the fence, as will be readily understood.

The gate may be raised to any intermediate point between its lowermost and highest positions, and secured at such point by hooking 15 one of the links of the chain I on the hook J.

It will be seen that my new and improved gate, when used as a farm-gate, can thus be raised to any height, so as to divide small stock 20 from larger stock, as will be readily understood, and can always be raised so as to swing easily open when the ground is covered with snow, being raised until it will clear the surface of the snow, when it is secured by the chain 25 in its adjusted position and can be swung open either way.

One of the most important features of this invention is that when the gate is thus suspended by placing the hook at the center of 30 the width of the top of the post and employing the chain, as shown and described, the greater part of its weight is supported on the chain from the center of the post, and thus it will be impossible for the gate to sag forward 35 at its top, which is a frequent annoyance with hinged gates. As comparatively little weight falls on the staples or eyebolts G G or upon the hinge rod or bar D, these parts will be 40 worn but very little and will last for a long time, the principal wear falling upon the links

of the chain, and as these are changed on the hook as the gate is adjusted up and down they will wear but little.

Having thus described my invention, what I claim, and desire to secure by Letters Patent 45 of the United States, is—

1. The combination, with the post having the beveled upper end, the hook secured in the said end at the center of its width, and the hinges or eyebolts, of the gate, the hinge bar 50 or rod having the threaded arms, the nuts on the same, and the upper perforated end and the adjusting-chain, substantially as and for the purpose set forth.

2. The combination, with the post having 55 the beveled longitudinal edges, the beveled upper end, the hinges or eyebolts, and the hook secured in the said upper end at the center of the same, of the gate having its rear post formed with the beveled edges and the transverse perforations, the hinge bar or rod having the threaded arms, the nuts on the same, and the upper perforated end and the adjusting-chain, substantially as and for the purpose 60 set forth.

3. The combination, with the post having the eyebolts, the hook secured in its upper end, and the gate having the transverse perforations, of the hinge bar or rod having the threaded arms formed integral with it and 70 having the perforated upper end and the adjusting-chain, substantially as set forth.

In testimony that I claim the foregoing as my own I have hereunto affixed my signature in presence of two witnesses.

WILLIAM B. THOMAS.
